UNITED STATES PATENT OFFICE.

RICHARD F. AUGUR, OF NEW YORK, N. Y., ASSIGNOR OF ONE-HALF TO RICHARD E. THIBAUT, OF NEW YORK, N. Y.

DISPLAY FOLDER.

Application filed September 26, 1925. Serial No. 58,891.

The invention relates to new and useful improvements in folders, and more particularly to a folder wherein one part of the folder swings relative to the other.

5 An object of the invention is to provide a folder of the above type wherein a display object may be caused to move across the face of the main section of the folder when said sections are swung relative to each other.

10 In the drawings—

Figure 1 is a perspective view of a folder embodying my invention;

Fig. 2 is a rear view of the folder with the sections closed one upon the other, and 15 showing in dotted lines the folder open;

Fig. 3 is a sectional view on the line 3—3 of Fig. 2;

Fig. 4 is a sectional view longitudinally 20 of the folder with the parts turned to wide open position;

Fig. 5 is a front view of the folder with the sections wide open and embodying the modified form of the invention, and

Fig. 6 is a sectional view on the line 6—6 25 of Fig. 5.

The improved folder comprises two sections movable relative to each other, and these sections are preferably made movable by hingedly connecting one section to the other, although the folder may be in one piece and creased so that one portion thereof can swing on the other. One of these sections, which will be referred to as the main section, is adapted to bear a display, and is provided with an opening. The other section will be referred to as a cover. The hinge between the two sections is in front of the rear edge of the cover, so that a portion of the cover projects in rear of the main section. This rearwardly projecting portion of the cover carries a bracket which is shaped so as to form an arm, and the end of the arm projects through an opening in the main section of the folder. The opening in the preferred form of the invention is a slot running at an angle to the axis of the hinge. On the end of the arm projecting through said slot, is an object. When the sections are swung either toward or away from each other, this object will be moved across the face of the main section.

Referring more in detail to the drawings, my improved folder consists of a main section 1 and a cover section 2. These sections are preferably made of paste board, cellu-

loid or some other similar material, and the main section 1 is creased or indented so as to form a hinge 3. The portion 4 of this main section in rear of the hinge 3 is secured to the cover section in any suitable way. This 60 provides a folder consisting of a main section and a cover section, which sections swing about an axis back from the edge of the cover section, or, in other words, it provides a cover section which projects in rear 65 of the main section. This main section is provided with a suitable display. In the preferred form of the invention, the main section is also provided with a longitudinal slot 5, which runs in a direction at an angle 70 to the axis of the hinge 3. The cover section 2 is extended so as to form a bracket 6. This bracket 6 is provided with a projecting arm 7, the free end of which is bent so as to extend through the slot 5 as indicated at 75 8. The portion 9 of the arm extending through the slot is formed into the shape of some object, as for example, a ship, as shown in Fig. 1 of the drawings. This bracket 6 is in rear of the main section, and when the 80 two sections are turned relative to each other, the bracket will turn about the end edge of the cover as the hinge and will cause the free end of the ship 9 to be moved along the slot 5 from one end to the other, and thus 85 give the appearance of a ship traveling along the surface of the sea which is displayed on the front part of the main section of the folder. It will readily be seen that the ship is caused to move by reason of 90 the fact that the edge of the cover extending in rear of the main section with which the bracket is formed a part, will be moved relative to the main section, as said sections are 95 swung one upon the other. It will be understood, of course, that the shaping of the portion 9 at the end of the arm may be varied according to what it is desired to display, and it is to be understood, therefore, that the invention broadly is not limited to the 100 specific structure shown in Fig. 1, but the structure may be varied so as to indicate the movement of any desired object along the face of the main section of the folder.

In Figures 5 and 6 of the drawings, I have 105 shown the folder used as an advertising folder to display a tire gauge. The folder sections are hinged in the same way and are provided with the same type of bracket. The end portion 9 is shaped so as to indicate 110

the plunger of a tire gauge, and the gauge marks are formed thereon. Preferably formed integral with the side edge of the main section 1 is a member 10 which is folded over on to the face of the main section and is held thereon by means of a projecting finger 11 which extends through a slot 12 in the main section of the folder. This portion 10 is the body portion of the tire gauge. The arm 7 of the bracket extends through a slot 13 in the main section of the folder, and this slot is in rear of the body portion of the tire gauge. When the folder is open, the end 9 of the bracket arm which represents the plunger of the tire gauge, will be moved into and out of the body portion 10 of the tire gauge.

In one form of the invention, the device is used for advertising purposes, as has been noted above. The display and movable object will, of course, be made so as to suit the character of the advertising. The invention, however, may be used for other purposes than advertising, as for example, 25 Christmas cards and the like, in which case, of course, the display and movable object will be made to suit the character of the use to which the folder is put. While I have shown in the drawings a folder made from 30 two sections glued or otherwise secured together along one edge thereof, so as to provide a hinge at a distance in front of the rear edge of the cover, when open it will be understood that the folder may be made 35 of a single piece of paste board, celluloid or the like, folded and creased so as to provide the two sections swinging one upon the other, but of course, the rearwardly projecting portion on one of the swinging sections 40 is necessary in order to support the bracket back from the line where one section swings on the other, and thus produce a movement in the object carried by the bracket. While I prefer to use a longitudinal slot through 45 which the end of the bracket may extend which carries the movable object, it will be understood, of course, that this slot may be shaped in any desired way, the only essential feature being that there is an opening in the 50 main section of the folder so that the object will be placed in front of the main section and move across the main section, while the means for moving it is in rear of the main section. Of course, it will be understood 55 that this object may be caused to move in other directions than horizontal. Here again, the essential feature is the utilizing of a projecting portion of one of the movable sections when the sections are swung relative to each other for causing the arm to move relative to the main section of the folder and thus move the object on the face thereof.

Having thus described the invention, what

I claim as new and desire to secure by Letters-Patent, is—

1. A folder comprising a main section, a cover section therefor, said sections being hingedly connected at a distance back from the edge of the cover section, a bracket member in rear of the main section and attached to said cover section in rear of the hinge and having a projecting portion adapted to extend through an opening in the main section of the folder and supporting a display object whereby when said cover section and main folder section are swung either away from or toward each other, the display object will be moved back and forth on the face of the main section.

2. A folder comprising a main section adapted to bear a display and having an opening extending lengthwise therewith, a cover section hinged to said main section and having a portion extending in rear of said hinge, a bracket connected to said extension of the cover portion and having a projecting arm, the free end of which extends through the opening in the main folder section and supporting a display object whereby when said folder sections are moved away from and toward each other, said display object will be moved back and forth on the face of said main section.

3. A folder comprising a main section having a slot formed therein and adapted to bear a display, an auxiliary section hinged to said main section, said hinge being located in front of the rear edge of said auxiliary section, a bracket attached to the auxiliary section and located in rear of said main section, said bracket having a projecting portion adapted to pass through an opening in the main section and bearing an object on the end thereof, whereby when said sections are moved away from and toward each other, said object will be moved back and forth on the face of the main section.

4. A folder comprising a main section and a cover section secured together along one edge of the folder, said main section being creased so as to swing on a hinge relative to the cover section and so as to provide an extension of the cover section in rear of the main section and movable with the cover section, said main section having a slot extending at an angle to the axis of the hinge and also having a display on the front face thereof, said cover section having an integral bracket extension shaped to form a projecting arm, which arm extends through said slot in the main section, the free end of said arm being shaped to form an object, whereby when said cover section is swung relative to the main section, said object is moved back and forth over the face of the main section.

In testimony whereof, I affix my signature.

RICHARD F. AUGUR.
